ANIMATED MUSIC BOX TOY

John W. Ryan, Bel-Air, Calif., assignor to Mattel, Inc., a corporation of California

Filed Feb. 1, 1966, Ser. No. 825

Term of patent 14 years

(Cl. D34—15)

Fig. 1

Fig. 2

FIG. 4

FIG. 1 is a perspective view of an animated music box toy showing my new design before actuation of its animating means;

FIG. 2 is a plan view of FIG. 1;

FIG. 3 is a side elevational view showing the side opposite to that shown in FIG. 1 after actuation of the animating means; and

FIG. 4 is a perspective view of FIG. 3.

I claim:

The ornamental design for an animated music box toy, as shown.
